CLAIM

The ornamental design for a laundry detergent packaging bag, as shown and described.

DESCRIPTION

FIG. 1 is a perspective view of the laundry detergent packaging bag showing our new design;

FIG. 2 is a front elevational view of the bag;

FIG. 3 is a rear elevational view of the bag;

FIG. 4 is a left side elevational view of the bag;

FIG. 5 is a right side elevational view of the bag;

FIG. 6 is a top plan view of the bag; and,

FIG. 7 is a bottom plan view of the bag.

The broken line showing of portions of the laundry detergent packaging bag is included for the purpose of illustrating environmental structure and forms no part of the claimed design.

1 Claim, 7 Drawing Sheets
